THOMAS O'DONNELL
ELIZABETH O'DONNELL INVENTORS

BY

Richard B. Owen

ATTORNEY.

UNITED STATES PATENT OFFICE.

THOMAS O'DONNELL AND ELIZABETH C. O'DONNELL, OF IRONWOOD, MICHIGAN.

ENVELOPE.

Application filed May 27, 1921. Serial No. 473,194.

To all whom it may concern:

Be it known that we, THOMAS O'DONNELL and ELIZABETH C. O'DONNELL, citizens of the United States, residing at Ironwood, in 5 the county of Gogebic and State of Michigan, have invented certain new and useful Improvements in Envelopes, of which the following is a specification.

This invention has relation to envelopes, 10 and more particularly to that class in which a string is confined within the end of the envelope by means of which the envelope may be unsealed or opened by drawing outwardly upon one end of the string. The 15 envelopes of this nature now commonly in use have not proved altogether successful because of the fact that the contents of the envelope are not easily removed therefrom even after the envelope has been opened by 20 pulling upon the string for the reason that this string is usually fixed in one corner of the envelope by means of one of the sealing flaps and this portion of the flap which is not cut by the string proves a hindrance 25 to the easy removal of the contents of the envelope.

The principal object of the present invention is to obviate this difficulty by providing 30 means for securing the end of the string which will in no way interfere with the removal of the contents of the envelope after the string has finished its cutting operation.

A further object of the invention is to 35 generally improve upon envelopes of this character by providing a device which will be of extremely simple, durable and inexpensive construction, one which is efficient and reliable in operation, and well adapted to the purpose for which it is designed.

With these and numerous other objects 40 in view, the invention resides in certain novel features of construction and the combination and arrangement of parts as will be hereinafter fully described and claimed.

45 In the drawing:—

Figure 1 is a front elevational view of the envelope,

Figure 2 is a rear elevational view thereof showing the same in an open position, and 50 Figure 3 is a section taken on the line 3—3 of Figure 2.

Referring to the drawing in detail it will be seen that 1 designates the body portion of the envelope which in the present illus-

tration is rectangular in shape and has secured to its lower edge the bottom flap 2 and to its side edges the side flaps 3 and 4 and to its top edge the sealing flap 5.

The parts thus far described are well known in the art and will be assembled in 60 the usual manner. Our invention consists in removing a portion of one of the flaps so that a tab may be secured to one of the edges of the envelope. In the present illustration this is accomplished by removing a 65 portion of the side flap 4 as shown at 6 and providing a tab 7 in this corner of the envelope. This tab 7 may be of any preferred shape but is preferably made substantially smaller than the flaps of the envelope. A string 8 is secured between the tab 7 and the body of the envelope in any preferred manner and the tab 7 will then be sealed to the body 1. In the present illustration a fastening means 9 is shown to 75 which is attached the string 8 at one of its ends, the other end thereof projecting through the bottom edge of the envelope. This fastening means 9 preferably consists of a metallic eyelet rivet and a stiffening 80 element 10 is associated therewith so as to be situated between body 1 and tab 7 as shown to advantage in Figure 3. The string is tied or otherwise secured about this fastening element 9 and situated along the side 85 edge of the envelope interiorly thereof throughout its major portion so as to terminate exteriorly of the envelope.

As has been stated this tab 7 is sealed or otherwise secured to the body 1 of the envelope so that as the letter sheet is placed in the envelope it will in no way hinder same. After the letter sheet is placed within the envelope the sealing flap 5 will be brought over upon the other flap of the envelope and sealed in the usual manner. When it is desired to remove the contents of the envelope all that the operator must do is to fold the end of the string outwardly thus cutting or severing the flap 4 from the 100 body 1 of the envelope. The fingers may now be placed in engagement with the letter sheet or other contents. As these contents are pulled from the envelope they will in no way be obstructed by the tab 7. In 105 string envelopes of the nature now under consideration which have heretofore been in practical use do not allow this easy re-

moval of the contents since the corner in which the string is permanently attached forms an obstruction to the removal of the contents and especially this is true when the 5 contents consists of ordinary letter sheet.

From the foregoing description, taken in connection with the accompanying drawings, the construction, operation, and advantages of an envelope of this character 10 will be readily appreciated without requiring an extended explanation. As numerous changes in form, proportion, and in the minor details of construction may be resorted to without departing from the spirit of 15 the invention we do not wish to be limited to the construction herein shown and described other than as claimed.

Having thus described our invention what we claim as new is:

An envelope including a body portion, a 20 plurality of flaps thereon, a tab at one corner of the body portion, a fastening element passing through the tab and the body portion, and a string located in one end of the envelope, one end of the string being 25 secured to the fastening element.

In testimony whereof we affix our signatures in presence of two witnesses.

THOMAS O'DONNELL.
ELIZABETH C. O'DONNELL.
